UNITED STATES PATENT OFFICE.

WILLIAM A. LEONARD, OF RIVERSIDE, ILLINOIS.

DESIGN FOR A SPOOL-CABINET.

45,886.

Specification for Design.

Patented June 2, 1914.

Application filed March 26, 1914. Serial No. 827,494. Term of patent 14 years.

To all whom it may concern:

Be it known that I, WILLIAM A. LEONARD, a citizen of the United States, residing at Riverside, in the county of DuPage and State of Illinois, have invented a new, original, and ornamental Design for Spool-Cabinets, of which the following is a specification, reference being had to the accompanying drawing, forming part thereof.

The figure shown in this drawing is a per-

spective view of a spool cabinet showing my new design.

I claim:

The ornamental design for a spool cabinet, as shown.

WILLIAM A. LEONARD.

Witnesses:

E. H. TILLSON,
E. V. GUSTAFSON.
